UNITED STATES PATENT OFFICE.

CHARLES E. McDONALD, OF BUTTE, MONTANA.

WINDOW-SHADE ROLLER.

Application filed May 31, 1924. Serial No. 717,030.

To all whom it may concern:

Be it known that I, CHARLES E. McDONALD, a citizen of the United States, residing at Butte, in the county of Silver Bow and 5 State of Montana, have invented certain new and useful Improvements in a Window-Shade Roller, of which the following is a specification.

This invention relates to a window shade 10 roller, and particularly to means for attaching thereto one end of a window shade to secure a firm but detachable connection therewith, and also for providing cooperating means for mounting the winding spring 15 for such a roller.

In this class of devices in order to secure a firm attachment of the shade to the roller it has been necessary to use driven fastening means which involve considerable labor 20 and care in properly aligning and securing the shade to effect its straight winding upon the roller and for securing the shade against disconnection when completely unwound at which time the strain extends radially to the 25 axis of the roller. This is particularly important in connection with metal shade rollers to which the attachment must be made by means of a retaining strip or plate and in such manner that the tension on the shade 30 will not displace the retaining means.

In prior constructions it has also been found difficult to secure a proper mounting for the winding spindle and its cooperating spring, particularly for the support of 35 one end of such spring upon a fixed part.

The present invention therefore seeks to provide an improved construction of shade roller provided with a longitudinal groove having seats at its opposite sides and a retaining member disposed in said groove to 40 engage said seats and also resiliently bear upon the inner wall of the groove so that the tension of the shade when completely unwound tends to increase the grip of the 45 retaining member thereon and effectually prevent disconnection.

A further object of the invention is to provide an improved construction of resilient retaining plate adapted to be disposed in a 50 groove of the shade roller and provided intermediate its edges with a bearing surface to engage the inner wall of the said groove.

Another object of the invention is to provide a novel construction of supporting 55 means for the winding spindle adapted for cooperation with a shade roller provided

with a longitudinal groove the inner wall of which is substantially flat, and comprises a bearing plate held against rotation by engagement with such wall and adapted to receive one end of the tension spring, the opposite end of which is connected to the spindle. 60

Other objects and advantages of the invention will be hereinafter set forth and the 65 novel features thereof defined by the appended claims.

In the drawing:

Figure 1 is a longitudinal section of the shade roller, the parts in elevation and 70 broken away;

Figure 2 is a section on the line 2-2 of Figure 1;

Figure 3 is a similar view on the line 3-3 75 of Figure 1;

Figure 4 is a like view on the line 4-4 of Figure 1;

Figure 5 is an enlarged cross section showing the position of the shade when completely unwound; 80

Figure 6 is a detail perspective of the retaining plate; and

Figure 7 is a modified form of the invention adapted for a wooden roller. 85

Like reference numerals refer to like parts throughout the several figures of the drawing.

In the preferred form of the invention the roller is formed tubular and of substantially circular form. It comprises the body 90 10 which is formed with a telescoping section 11 providing for the adjustment in length of the roller to fit the windows of different widths. These sections of the body are each provided upon their circumference with a grooved portion 12 which is formed at one side with a holding seat 13 for a retaining plate 14 and at the opposite side with an elongated lip or tongue 15 which provides a recess into which the shade or curtain 16 is introduced. The inner wall 17 of the groove 12 extends substantially chordal to the circumference of the roller and provides a bearing surface cooperating with the retaining plate 14 as hereinafter 95 described.

This plate is formed at one edge with a flange 18 adapted to seat against the shoulder or seat 13 and the opposite edge of the plate comprises a gripping edge 19 to engage the shade which may be serrated if desired to secure additional engagement there- 100 105 110

with. Intermediate the edges 18 and 19 the plate is formed with a curved bearing surface 20 which as shown in Figure 5 contacts against the inner wall 17 of the groove 5 while the oppositely curved face 21 of the plate forms a substantially continuous curved surface for the roller. As shown in Figure 6 this plate may be formed upon a compound curve and may either extend 10 for the longitudinal length of the roller or be formed in separate sections applied for the attachment of a shade.

A modified form of the invention is shown in Figure 7 where the holding function is substantially the same and in this modification the roller 22 is formed of wood and provided with a groove upon its periphery having opposite dove-tailed faces 23 and 24 adapted to receive and retain a strip 20 25 of resilient wood or similar material introduced longitudinally of the roller. This strip 25 is provided intermediate its side edges with a groove 26 adapted to seat upon a rib 27 carried by the inner face of 25 the groove within the roller. The groove and rib cooperate to place a lateral tension upon the strip 25 causing the opposite ends thereof to tightly grip the dove-tailed seats and also forming a point of contact between 30 the strip and the inner wall of the groove by which a supplemental holding of the shade 28 is secured as shown in Figure 7. In this illustration the shade is gripped at the seat 23 and also between the rib and 35 groove at the inner wall of the recess. As a result, the tension upon the shade when completely unwound causes additional tension to be applied at all the holding points as indicated by dotted lines in Figure 7 as 40 the strain upon the strip 25 causes the same to more tightly engage the seat 23 and also the rib 27 of the roller.

The construction of roller above described is also adapted to cooperate with a novel 45 form of mounting for the spring winding tension and this structure comprises a bearing plate 30 having a circular flange 31 engaging the inner periphery of the body 10 and having one segment of its outer edge 50 removed, as indicated at 32 in Figures 3 and 4, so as to seat upon the inner wall 17 of the groove 12 extending longitudinally of the roller. This retains the plate against any rotative movement and forms a firm 55 support for the attachment of the winding spring 33 as shown in Figure 1. This spring may be attached to the plate in any preferred manner, for instance by means of a lug 34 bent outwardly therefrom, and the 60 plate is further formed with a central bearing 35 to receive the inner end of the winding spindle or shaft 36 which is held against displacement by a suitable collar 37 secured thereon.

65 The opposite end of the spindle 36 is pro-

vided with a bearing 38 in the cap 39 which is frictionally retained upon the body 10 of the roller. This retention is desirably secured by means of cooperating projections and depressions formed respectively upon 70 the body and cap, as indicated at 40. The spindle 36 is also formed with a lateral lug 41 to which one end of the spring 33 is secured, and this spring is held in its tensioned position by the usual pawl and 75 ratchet construction not shown.

In the construction shown in Figure 1 the opposite pivot 42 of the roller is rotatably mounted in the cap plate 43 by means of a bearing portion 44 and the flange 45 80 of this cap extends within the telescoping section 11 of the roller. This cap is frictionally held in position by projections and seats 46 similar to those shown at 40 upon the opposite end of the roller.

In the construction shown in Figures 1 to 6 it will be seen that the construction of the attaching groove and the retaining plate provides for a plurality of gripping surfaces to engage the shade or curtain 90 attached to the roller while the outer portion of this plate forms a substantially continuous circular face for said roller to secure an even winding of the shade thereon.

Referring to Figure 5 it will be seen that 95 the shade is normally gripped and retained by contact of the plate with the end of the lip at one side of the groove while the inner end of the plate also retains the shade in contact with the inner face of this lip while 100 the portion of the shade near its free end is further held by contact of the plate with the inner wall of the groove. This effectively prevents any danger of disconnection if strain is placed upon the shade when 105 completely unwound as such strain when applied is transmitted to the retaining plate causing it to engage more firmly the free edge of the lip and also the inner face thereof as well as the inner wall of the groove. 110 The plate being of resilient character increases its gripping tension at the several points under such strain.

This form of retaining plate is adapted 115 to be inserted laterally into the groove with the shade folded thereover and retained by engagement with the holding shoulder thereof so that the strain upon the plate increases the contact with this shoulder and prevents the plate from being sprung or accidentally withdrawn from the groove of the roller. The inner face of this groove also cooperates with the pivoting plate for the winding spindle to prevent rotation thereof so that the invention not only presents an 120 improved form of attaching means but also of a mounting for the winding spring and its spindle.

The construction of the telescoping roller 125 permits longitudinal adjustment thereof to 130

properly fit different widths of windows or previously attached brackets, while the frictionally retained caps permit ready access to the interior of the roller when it is necessary to withdraw or repair the spring as these several parts can be withdrawn as a unit since the bearing plate is carried by the inner end of the spring spindle. It will be obvious that such a construction is also applicable to other forms of roller than that specifically before described.

While the specific construction of the attaching means and spring mounting have been shown and described, the invention is not confined thereto as changes and alterations may be made without departing from the spirit of the invention as defined by the following claims.

Having thus described my invention, what I claim as new and desire to secure by Letters Patent is:

- 20 1. A shade roller provided with a longitudinal groove having a seat at one side and a projection at its opposite side, and a resilient retaining member disposed in said groove to abut said seat and having a free portion transversely movable to engage the inner walls of the groove and the projection at opposite points.
- 25 2. A shade roller provided with a longitudinal groove having a seat at one side and a lip at the opposite side, and a resilient retaining plate engaging said seat and having a free edge within said lip and a bearing surface intermediate its edges to engage

the inner wall of the groove upon tension applied to said free edge.

3. A shade roller provided with a longitudinal groove having a holding seat at one side and an opposite elongated lip, and a metal retaining plate formed at one edge with a face to engage said holding seat and having its opposite outwardly bent face edge adapted to contact with the inner face of said lip.

4. A shade roller provided with a longitudinal groove having a holding seat at one side and an opposite elongated lip, and a resilient retaining plate formed at one edge with a face to engage said holding seat and at its opposite edge with an outwardly bent free edge adapted to contact with the inner face of said lip and also with a frictional holding face intermediate said edges disposed to engage the inner wall of the groove.

5. A shade roller provided with a longitudinal groove having a holding seat at one edge and an opposite elongated lip, and a resilient metal retaining plate having its body formed upon a compound curve with one side edge formed with a shoulder adapted to engage said holding seat and its opposite free edge disposed outwardly to engage the inner face of said lip and an intermediate face disposed to engage the projected edge of said lip.

In testimony whereof I affix my signature.

CHARLES E. McDONALD.
